UNITED STATES PATENT OFFICE.

MARSHALL COOK, OF CHICAGO, ILLINOIS, ASSIGNOR OF ONE-HALF TO GARRETT J. REIDY, OF CHICAGO, ILLINOIS.

WRENCH.

1,361,518.

Specification of Letters Patent. Patented Dec. 7, 1920.

Application filed March 11, 1920. Serial No. 364,959.

To all whom it may concern:

Be it known that I, MARSHALL Cook, a citizen of the United States, residing at Chicago, in the county of Cook and State of Illinois, have invented new and useful Improvements in Wrenches, of which the following is a specification.

This invention relates to wrenches having a shank carrying a sliding jaw which is locked on the shank by a transversely slideable pawl engaging a rack thereon.

The invention relates more particularly to the locking means of the slideable jaw, and its object is to provide a simple and efficient pawl and rack catch which will securely hold the jaw in adjusted position, and which can be easily controlled.

The object stated is attained by means of a combination and arrangement of parts to be hereinafter described and claimed, and in order that the same may be better understood, reference is had to the accompanying drawing forming a part of this specification.

In the drawing, Figure 1 is an elevation of the wrench; Fig. 2 is a cross section showing the jaw adjusting means, and Fig. 3 is a detail in perspective.

Referring specifically to the drawing, 5 shank 5 denotes the shank of the wrench, provided at its outer end with a fixed jaw 6, and carrying a slideable jaw 7 to coöperate with the latter in the usual manner.

The front edge of the shank 5 has a rack 35 8 engageable by a pawl 9 carried by the jaw 7, for locking the latter in adjusted position on the shank. That portion of the jaw 7 which is opposite the rack edge of the shank has a recess 10 opening to said edge, 40 and seating the pawl 9, the latter being positioned transversely with respect to the shank, and slideable in the recess to engage the rack. The rack engaging end of the pawl is beveled so that the pawl automatically slips back when the jaw 7 is slid along the shank in the direction of the fixed jaw 6. Between the rear end of the pawl and the opposite wall of the recess in which it is mounted, is located a spring 11 for advancing the pawl to holding position.

The recess 10 housing the pawl 9 is con-

tinued through the rear face of the jaw 7 in the shape of a slot 12 to seat a web 13 extending from the pawl and terminating in a flat plate-like enlargement 14 seating 55 against said rear face of the jaw, said part 14 having an aperture 15 through which shank 5 passes. Opposite the rear edge of the shank, the part 14 is formed into a finger piece 16, which latter, when it is pressed 60 inwardly, or in the direction of the shank, slides the part 14 transversely of the shank, and as the pawl 9 is joined to said part 14 by the web 13, the pawl is backed to clear the rack 8. The jaw 7 is now free to be 65 backed from the jaw 6, and upon releasing the finger piece 16, the spring 11 advances the pawl into locking engagement with the rack, to lock the jaw 7 to the shank 5. It will be understood that the aperture 15 is 70 longer than the width of the shank 5, in order to permit the part 14 to be operated as described. The pawl 9 is wider than the slot 12 and the web 13, so that the pawl is prevented from dropping out of the recess 10. 75

The wrench is strong and durable, and the jaw 7 will be securely held in adjusted position by the pawl 9. If the rack 8 should become worn out from long continued use 80 of the wrench, or if some of the rack teeth should break, the shank 5 can be removed and replaced by a new one.

I claim:

A wrench having a shank provided with 85 a rack, a jaw slideable on the shank, and having a recess opening to the rack, and a slot leading from said recess and opening through the rear face of the jaw, a pawl slideably seating in the recess to engage the rack, and having a web seating in the slot, the width of the slot being less than that of the pawl to prevent the passage of the latter therethrough, and a plate carried by the web, said plate seating against the rear face 90 of the jaw and having a slot through which the shank passes, said plate being slideable on the shank transversely thereof to disengage the pawl.

In testimony whereof I affix my signature. 100

MARSHALL COOK.
